No. 37,294.

Patented January 17, 1905.

UNITED STATES PATENT OFFICE.

ISAAC ROSENBAUM, OF MOUNT VERNON, INDIANA.

DESIGN FOR A FINGER-RING.

SPECIFICATION forming part of Design No. 37,294, dated January 17, 1905.

Application filed June 1, 1904. Serial No. 210,751. Term of patent 7 years.

To all whom it may concern:

Be it known that I, ISAAC ROSENBAUM, a citizen of the United States, and a resident of Mount Vernon, in the county of Posey and 5 State of Indiana, have invented a new, original, and ornamental Design for a Finger-Ring, reference being had to the accompanying drawings, in which—

Figure 1 is a perspective view of a finger-ring, illustrating my new design; and Fig. 2 10 is a front elevation thereof.

What I claim as new, and desire to secure by Letters Patent, is—

The ornamental design for a finger-ring herein shown.

ISAAC ROSENBAUM.
